DESIGN FOR A PHOTOGRAPHIC LIGHTING UNIT

Henry J. Hood, Rochester, N. Y., assignor to Eastman Kodak Company, Rochester, N. Y., a corporation of New Jersey

Application August 16, 1940, Serial No. 94,450

Term of patent 14 years

To all whom it may concern:

Be it known that I, Henry J. Hood, a citizen of the United States, residing in Rochester, in the county of Monroe and State of New York, have invented a new, original, and ornamental Design for Photographic Lighting Units, of which the following is a specification, reference being had to the accompanying drawing, forming part thereof.

In the drawing:

Fig. 1 is a front elevational view of a photographic lighting unit showing my new design.

Fig. 2 is a top plan view of the same.

I claim:

The ornamental design for a photographic lighting unit, as shown.

HENRY J. HOOD.
